UNITED STATES PATENT OFFICE.

MILLER REESE HUTCHISON, OF WEST ORANGE, NEW JERSEY.

SOUND CONTROLLER FOR TELEPHONE RECEIVERS.

Application filed January 22, 1924. Serial No. 687,736.

To all whom it may concern:

Be it known that I, MILLER REESE HUTCHISON, a citizen of the United States, and resident of West Orange, in the county of Essex 5 and State of New Jersey, have invented certain new and useful Improvements in Sound Controllers for Telephone Receivers, of which the following is a specification.

Telephone receivers vary widely in the 10 loudness of the sound produced and also with respect to the noisiness of the environment in which they are used and my present invention contemplates means for closing in the transmitter outlet and conducting the 15 sound through a suitable conduit, thus providing means whereby the above variations can be taken care of.

Where the sounds are very faint, they may 20 be conducted through tubes terminating in ear-pieces closely fitting into the ear. Similar advantage exists where the sounds are not particularly faint but the surroundings are very noisy; also where the received sounds are loud, and the surroundings quiet, 25 so that the sounds are audible to bystanders near or even at a considerable distance from the receiver.

To meet any or all such conditions, I provide a simple device readily attachable to 30 the standard telephone receiver. Preferably it is in the form of a cover plate, firmly attachable so as to permit use with the telephone receiver lying on its side or hanging up or standing on end. Preferably the outer 35 face of the device is finished off to form a plane stable base of support.

The above and other features of my invention may be more fully understood from 40 the following description in connection with the accompanying drawings, in which—

Fig. 1 is a face view of the device with attached ear-tubes;

Fig. 2 is a section on the line 2—2, Fig. 1;

Fig. 3 is a section on the line 3—3, Fig. 1;

45 Figs. 4 and 5 are respectively face view and side elevation of a simple form of stamping that may be employed as indicated in the preceding figures;

Fig. 6 is a face view corresponding to

50 Fig. 1 but showing a modification;

Figs. 7 and 8 are respectively sections on

the lines 7—7 and 8—8, Fig. 6;

Fig. 9 is a section like Fig. 2, but showing

a modification;

55 In Figs. 1 to 5 the device comprises a cover member 1, preferably a die casting,

one face of which has an annular depression 2 of approximately the same diameter as the face annulus 3 of the telephone receiver, outside of which depression is an annular 60 surface 4. At the center is a projecting boss 5, formed with a passage 6 adapted to register with the sound outlet 7 of the telephone receiver. The passage 6 extends away from the receiver far enough to clear the face 65 thereof and then curves into the tubular portion 8 which is continued through a projection 9, extending beyond the periphery of the cover piece 1. Preferably the back 70 of the cover is contoured so that the back wall 10 of passage 8 appears in relief and there is an annular base portion 11 projecting into the same plane as 10, so that the cover may be laid on its back with the receiver projecting upward at right angles 75 thereto. Preferably the annulus 11 has a molded depression 12, in which may be located the name of the maker, trade-name or any other desired legend, the letters or figures being preferably molded in the metal. 80

The boss 5 has exteriorly thereof a sleeve 13, preferably of flexible rubber, which projects into the sound outlet 14 of the telephone receiver, this affording a sealed coupling with tube 6. If desired, the tube 13 may be provided with a bead 15 to assist in sealing the joint and also to prevent the tube from being pushed into contact with the receiver diaphragm. 85

In the form shown, the cover, 1, is secured 90 to the receiver by means of a sheet metal stamping, molded as at 20 to fit the portion 2 of the cover and at 21 to fit the annulus 4. The stamping is centered by central perforation 22, which fits around the outside of the 95 tubular boss 5 and may be secured to the cover by screws engaging perforations 26. Around the edges of the stamping are integrated forwardly projecting arms 23, 23, terminating in eyes 24 formed by curling the 100 metal preferably outward. These arms embrace the telephone receiver, as shown in Fig. 2 and are clamped against the periphery thereof by springs, preferably a continuous helix 25. The arms 23, have radial portions 105 at their bases that contact with annulus 4, thereby increasing springiness and decreasing liability of permanent bends or breaks at the base of the arms.

The device even as above described may 110 be applied to the receiver and the receiver cover member 1, preferably a die casting, held in the hand of the operator in the

hand of the operator in the

usual way, so that the outlet 27 of passage 8 may be brought nearer to or farther away from the ear, according to conditions. Preferably, however, the projection 9 is formed 5 to receive an ordinary ear tube outlet such as is commonly used on phonographs and may include a tube 28, communicating with a metal Y 29, communicating through its two branches with tubes 30, 30, terminating 10 in ear-pieces 31, 31 and preferably provided with an internal spring wire stiffener 32, which has a set tending to press the ear-pieces into place in the ears of the user.

The spring 25 is a desirable means of 15 holding the arms 23 in clamping relation to the receiver, but if desired these arms may be contoured as at 23^a, Fig. 9, to fit the outside of the telephone receiver, and re-curved as at 24^a, to form wedge surfaces to assist 20 in opening the spring fingers when the device is applied to the telephone receiver.

In the form shown in the Figs. 6, 7 and 8, I have provided means for more accurately centering and more positively securing 25 the attachment to the telephone receiver. In this form rigid guiding at three points is combined with resilient clamping at three other points. The rigid guiding is afforded by the three integral forwardly projecting 30 arms 40 having the recesses 41 formed on the outside thereof, and having their inner faces 42 parallel with each other. These faces are exactly concentric with the central tubular boss 5 and they have sliding 35 fit with the outside of the receiver so that tube 5 is accurately centered for registry with the sound outlet of the receiver. Co-operating with each of these fixed guides, and preferably opposite them, are the 40 three movable guides 50, 50, pivoted as at 51 in radially projecting ears 52, 52. These are clamping guides contoured as at 53 to fit the end of the telephone receiver and they have peripheral recesses 54 corresponding 45 to the recesses 41 in the fixed guides. These six recesses all in the same plane receive a resilient clamping rim which may be a spring 25, similar to that of Figs. 2 and 3.

The transmitter engaging face of the 50 cover may have a facing of felt, rubber or other non-vibratory cushioning metal.

The diameters of the passages leading to the ear may be predetermined to suit the user. Passages of large cross-section may 55 be used to deliver sound energy intense enough for those who are very hard of hearing, while the average user may have the passages as small as desired, so as to damp the sound wave by friction. Adjustable damping, is possible by using large tubes, the walls of which may be pinched by the user, to any desired extent.

I claim:

1. An attachment for telephone receivers, 65 consisting of a flat disc-like member for

closing the outlet of the receiver and having peripheral clamps for holding it on the receiver, a projecting tube centrally arranged to register with the sound outlet of the receiver, a rubber coupling on said tube having a cylindrical portion projecting into and fitting said sound outlet. 70

2. An attachment for telephone receivers, consisting of a flat disc-like member for closing the outlet of the receiver and having means for holding it on the receiver, a projecting tube centrally arranged to register with the sound outlet of the receiver and connected to a radial passage extending beyond the periphery of the disc, a rubber coupling on said tube having a cylindrical portion projecting into and fitting said sound outlet and provided with an internal bead engaging the outer surface of the transmitter to limit the depth of such projection. 80

3. A device for supporting a telephone receiver on the sound outlet end comprising an integral disc member having an opening in its inner face to register with the receiver outlet and communicating through a radial 90 passage with the outer air, the outer face of the disc having a radial passage molded as a radial pipe of minimum permissible thickness and a marginal rim of approximately the same thickness as the pipe cooperating therewith to afford a plane surface of support. 95

4. A device adapted to serve as a stand for a telephone receiver, consisting of a disc the inner face of which covers the outlet 100 end of the receiver and the outer face of which has a radial pipe formed as a molded projection thereon and communicating with an integral tubular boss projecting centrally from the inner face of the disc, said outer face having also distributed support projections of approximately the same thickness as the projection of the radial pipe. 105

5. A device adapted to serve as a stand for a telephone receiver, consisting of a disc the inner face of which covers the outlet 110 end of the receiver and the outer face of which has a radial pipe formed as a molded projection thereon and communicating with an integral tubular boss projecting centrally 115 from the inner face of the disc.

6. An attachment for telephones comprising a disc member, having on its inner face a circular depression the annular edge of which fits the annular molding on the end 120 of the receiver to center the same, in combination with parallel clamping fingers fitting the receiver peripherally and an elastic ring clamping the ends of fingers toward the axis of the receiver. 125

7. An attachment for telephone comprising a disc member, having on its inner face a circular depression the annular edge of which fits the annular molding on the end 130 of the receiver to center the same, in combi-

nation with parallel clamping fingers fitting the receiver peripherally and an elastic ring clamping the ends of fingers toward the axis of the receiver, portions of said ring between the fingers engaging behind the flange of the receiving cover.

8. An ear tube and means for securing it to a telephone receiver, said means comprising a disc member which fits against the out-

let end of the receiver, in combination with 10 parallel clamping fingers on the disc engaging member, fitting the receiver peripherally and an elastic ring clamping the ends of fingers toward the axis of the receiver.

Signed at New York in the county of New ¹⁵ York and State of New York this 18th day of January, A. D. 1924.

MILLER REESE HUTCHISON.
